UNITED STATES PATENT OFFICE.

HENRIK HILLBOM, OF WALLINGFORD, CONNECTICUT, ASSIGNOR TO R. WALLACE & SONS MFG. CO., OF WALLINGFORD, CONNECTICUT, A CORPORATION.

DESIGN FOR A HANDLE FOR SPOONS, FORKS, OR SIMILAR ARTICLES.

SPECIFICATION forming part of Design No. 35,975, dated July 8, 1902.

Application filed May 12, 1902. Serial No. 107,044. Term of patent 7 years.

To all whom it may concern:

Be it known that I, HENRIK HILLBOM, of Wallingford, in the county of New Haven and State of Connecticut, have invented and produced a new, original, and ornamental Design for a Handle for a Spoon, Fork, or Similar Article, (Case B;) and I do hereby declare the following, when taken in connection with the accompanying drawing and the letters 10 of reference marked thereon, to be a full, clear, and exact description of the same, and which said drawing constitutes part of this specification, and represents in a face view a handle for a spoon, fork, or similar article 15 illustrating my design.

This invention relates to a design for a handle for a spoon, fork, or similar article; and it consists in the ornamentation as shown in the accompanying illustration.

Raising from a fleur-de-lis A near the center of the handle is a partially-draped female figure B with arms upraised and surrounded by cupids C, while the edge of the handle is bordered by scrolls D and surmounted by a leaf-like tip E.

Having fully described my invention, what I claim as new, and desire to secure by Letters Patent, is—

The ornamental design for a handle for a spoon, fork or similar article as herein shown 30 and described.

In testimony whereof I have signed this specification in the presence of two subscribing witnesses.

HENRIK HILLBOM.
